ARTHUR W. THOMPSON, OF EAST MCKEEPORT, PENNSYLVANIA, ASSIGNOR TO WESTINGHOUSE ELECTRIC & MANUFACTURING COMPANY, A CORPORATION OF PENNSYLVANIA

CHEMICAL CONTAINER

Application filed October 21, 1924. Serial No. 745,040.

My invention relates to electrical translating devices having an inert atmosphere confined above the fluid level therein, and particularly to chemical containers for removably housing the chemical compounds employed in such electrical translating devices.

One object of my invention is to provide a chemical container that shall be adapted for ready insertion into, and removal from, apparatus for supplying an inert atmosphere in electrical translating devices.

Another object of my invention is to provide a chemical container that shall have provision for circulating gas through the chemicals contained therein.

A further object of my invention is to provide a chemical container for a plurality of separate chemical compounds that shall be adapted for passing gas through one of the chemicals contained therein only or through a plurality of such chemicals in series relation.

In electrical translating devices, such as circuit interrupters and transformers, in which an inert atmosphere is maintained above the level of an insulating fluid, it has been found most satisfactory to supply factory-filled cartons containing the proper quantities of chemical compounds that may be easily inserted into the electrical translating devices at the places where such devices are in use.

In the accompanying drawings, Figure 1 is a plan view of a chemical container embodying my invention.

Fig. 2 is a view, partially in elevation and partially in section, taken along the section line II-II of Fig. 1.

Fig. 3 is a fragmentary sectional view of my improved chemical container taken along the section line III-III of Fig. 1.

My invention comprises, in general, a container 1 in which a plurality of chemicals 2 and 3 are separated by partitions 4 and 5 in such manner that a gas space 6 is left between the chemicals for co-operation with a tube 7 for creating circulating atmosphere through the chemical compound 2.

The container 1 is preferably of a transpar-

ent material, such as a glass jar, in order that the condition of the chemical compound 2 may be observed. The chemical compound 2 is known as a deoxidizer for the reason that it removes oxygen from the gas circulating therethrough. Before being oxidized, the color of the chemical compound is brown but, after oxidization, it turns to a robin's-egg blue color, with a very distinct color line separating the used from the unused material. Accordingly, with a transparent container, an operator is enabled, at a glance, to tell the chemical condition of the compound. The composition of the deoxidizer is as follows:

	Per cent by weight
Copper scale, finely ground	58
Kieselguhr (filter cel)	8
Ammonium chloride	25
Calcium chloride and water	9 70

The chemical compound 3 is preferably calcium chloride or some other chemical having an affinity for water in order to absorb moisture from gases passing therethrough. The chemical compound 2 is confined by the partition 4, the latter being provided with a plurality of perforations 8 for the purpose of permitting gas to pass from the chemical compound 2 to the gas space 6.

The partition 5 is provided with an upstanding cylindrical lug 11 that terminates in a threaded portion 12 to co-operate with a cap 13 and a washer 14 for providing a gas outlet from the gas space 6 upon the removal of the cap 13. The partition 5 is also provided with an annular flange 15 that is provided with a plurality of outwardly-extending ears 16 for co-operation with the walls of the casing 1 in supporting the partition 5 and the chemical 3. A cover 17 is placed above the chemical 3 for confining the latter.

The cover 17 is provided with a plurality of outlets 18 and 19, somewhat similar in construction to the outlet 11, for permitting the circulation of gas through the chemical 3. Outlets 18 and 19 extend downwardly to different depths in the chemical 3 in order to insure a circulation of air through the chemical compound. A porous strip of material 100

20 extends from the outlet 18 into the chemical compound 3 in order to insure a more uniform consumption of the chemical compound. A suitable sealing compound 21 is run between the flange 15 and the casing 1 and between the cover 17, the flange 15 and outlet in order to render the container air tight. The edges of the partition 4 are likewise sealed to the container 1.

10 The sealing compound is preferably of an acid-resisting material having an asphalt base, such as numerous compounds used in connection with storage batteries. The outer portion is a soft easily fusible material while 15 the inner portion is a harder material. The outer portion effectively seals the container 1 while the inner portion keeps the softer material from the chemical.

10 The tube 7 is preferably of lead and extends outwardly to an outlet 22 that is similar in structural details to the outlet 11. The tube 7 is surrounded by the sealing compound 21 where the former passes through the partitions 4 and 5 and it is also separated from 25 the chemical compound 2 by a coating of the sealing compound 21. By coating the tube 7, throughout its entire length, with the sealing compound 21, the tube is protected from the chemical action of the deoxidizer 2 and, 30 at the same time, it is maintained in its proper position relative to the container 1. The lower end of tube 7 extends inwardly, as at 23, to approximately the center of the container and adjacent to the bottom thereof. 35 The end 23 of the tube is immediately surrounded by a porous material 24, such as asbestos wool, in order that gas entering the container therethrough may be more uniformly distributed to the chemical compound 2. A brass screen 25 is interposed between 40 the asbestos wool 24 and the chemical compound 2 in order to confine the asbestos wool.

When it is desired to utilize the chemicals contained in the casing 1, the caps from outlets 11 and 22 are removed and suitable unions are attached to the threads 12, for connection to the electrical translating device in service. Upon the connection of the outlets 11 and 22 to a suitable pipe network, such as 50 is shown in the copending application of Leland H. Hill, Serial No. 753,836, filed Dec. 4, 1924, and assigned to the Westinghouse Electric & Manufacturing Company, gas circulates downwardly through the tube 7, the asbestos wool 24, the deoxidizing chemical 2, the perforations 8 in the partition 4, the gas space 6 and the outlet 11. Expansion of the chemical compound 2 in use is cared for by the breaking of the sealing compound 55 21 by the partition 4, which moves upwardly into the gas space 6, rather than causing the bursting or distortion of the container 1.

If it is desired to subject the gas to a drying action, the caps are removed from the 60 outlets 18 and 19 and connection made to a

pipe system, such as is disclosed in the aforementioned Hill application, and the gases may be passed through the dehydrating chemical 3 after having passed through the deoxidizing chemical 2. It is to be understood, however, that the manner in which the gases are conducted externally of the container between the several outlets 11, 18, 19 and 22 constitutes no part of the present invention, except in so far as it is necessary to 70 set forth the reasons for the structural details found in the container itself.

It will thus be seen that I have provided a chemical container that is transparent, in which a plurality of chemicals are held in mechanical separation and, at the same time, a gas may be made to circulate through one or both of the chemicals by making proper external connections to the container. My chemical container is of such shape that it 80 may be readily shipped, and the chemicals are so sealed in that danger of their being contaminated by being exposed to the atmosphere during shipment is avoided.

I do not wish to be restricted to the specific arrangement of parts herein set forth, as various modifications thereof may be effected without departing from the spirit and scope of my invention. I desire therefore, that only such limitations shall be imposed as are indicated in the appended claims.

I claim as my invention:

1. A chemical container comprising a plurality of perforated partitions for sub-dividing the jar into compartments, a tube extending downwardly through the partitions from the exterior of the casing to the bottom thereof, a sealing compound surrounding the tube, and a body of porous material surrounding the inner end of the tube.

2. A chemical container comprising a jar, a plurality of perforated partitions for sub-dividing the container into compartments, a tube extending from the exterior of the jar to the bottom and center thereof, a sealing compound surrounding the tube, and a body of porous material occupying the lower central portion of the container jar surrounding the inner end of the tube.

3. A chemical container comprising a plurality of perforated partitions for sub-dividing the container into compartments, a chemical compound in the lower compartment, a tube extending downwardly from the exterior of the container to the bottom and center thereof, a sealing compound surrounding the tube, a body of porous material occupying the lower central portion of the container surrounding the inner end of the tube, and a screen for separating the porous material from the adjacent chemical compound.

4. A chemical container comprising a plurality of perforated partitions for sub-dividing the container into compartments, a chemical compound in the lower compartment, a

5 tube extending downwardly from the exterior of the container to the bottom thereof, a sealing compound surrounding the tube, a body of porous material surrounding the inner end of the tube, and a screen for separating the porous material from the adjacent chemical compound.

10 5. In a chemical container, a casing, a perforated partition disposed therein, a chemical compound confined by the partition, a tube extending upwardly from the bottom of the chemical compound through the partition to the exterior of the casing, and a second partition spaced slightly above the first partition thereby defining a gas space, the second partition being provided with an upwardly-extending outlet from the gas space to the air whereby a gas may be passed through the chemical compound.

15 6. In a chemical container, a casing, a perforated partition disposed therein, a chemical compound confined by the partition, a tube extending from the bottom of the chemical compound through the partition to the exterior of the casing, a second partition spaced slightly above the first partition thereby defining a gas space, the second partition being provided with an outlet from the gas space to the air, a second chemical compound supported by the second partition, a cover member for confining the second chemical and a sealing compound for securing the casing tube, cover member and partitions in gas-tight engagement, whereby a movement of gas may be created through the first chemical compound only.

20 7. In a chemical container, a casing, a perforated partition disposed therein, a chemical compound confined by the partition, a tube extending from the bottom of the chemical compound through the partition to the exterior of the casing, a second partition spaced slightly above the first partition thereby defining a gas space, the second partition being provided with an outlet from the gas space to the air, a second compound supported by the second partition, a cover member for confining the second chemical compound, the cover member being provided with a plurality of outlets, communicating with the second chemical compound, and a sealing compound for securing the casing, tube, cover member and partitions in gas-tight engagement, whereby a movement of gas may be created through the first chemical only, or through the first and second chemicals in series relation.

25 In testimony whereof, I have hereunto subscribed my name this first day of October, 1924.

30 ARTHUR W. THOMPSON.
